UNITED STATES PATENT OFFICE.

CLARENCE COLEMAN, OF NEWCASTLE, INDIANA.

BASE-SHIELD FOR PIANOS.

1,028,544.

Specification of Letters Patent.

Patented June 4, 1912.

Application filed January 24, 1912. Serial No. 673,018.

To all whom it may concern:

Be it known that I, the undersigned, CLARENCE COLEMAN, a citizen of the United States, residing at Newcastle, in the county 5 of Henry and State of Indiana, have invented certain new and useful Improvements in Base-Shields for Pianos, of which the following is a specification.

This invention relates to improvements in 10 shields or protector guards for pianos.

In the business of handling pianos, including that of moving and transporting the pianos in the shipping room and freight depots, and of shifting same for demonstrating 15 and for displaying purposes in sales rooms, and in the cleaning of the floor surfaces about them, the polished surfaces of the bottom or base portions of the legs and of the piano body are subjected to scratches 20 and to bruises, and to being soiled with dirt and dust, or to being spotted with moisture or other deleterious substances. Such injuries to the said highly finished and polished surfaces must be fully repaired and 25 the evidences thereof entirely removed. The work of doing this class of repairing calls for the best and most painstaking skill in scraping, rubbing, patching, oiling off and re-polishing; and besides the fact that 30 the services of artisans competent for the work are not readily obtainable, the work of said repairing is expensive and is a serious inconvenience to the manufacturer, as well as to the wholesale and to the retail 35 merchant.

To provide a guard shield or protecting guard capable of being practicably attached to the piano, and which will effectively prevent the liability of the inflicting on the 40 lower portions of the piano body and legs, of injuries of the character above referred to, are the general objects of this invention.

More specific purposes of the invention are to provide a guard of the character 45 above referred to which will be simple and economical of construction, rugged and durable, and which may be used for pianos of the minimum as well as the maximum width.

With the foregoing objects in view my 50 present invention consists of the new construction, combination and arrangement of parts described in this specification and defined in the appended claims, and illustrated in the accompanying drawings wherein the 55 several parts of the invention are designated

by similar characters of reference throughout the different views, in which—

Figure 1 is a plan view, and Fig. 2 is a perspective view of my improved base shield for pianos. Fig. 3 is a perspective view of 60 a piano, the base shield being attached to same. Fig. 4 is a view showing the relative position of the intermediate member of the shield frame when the device is attached to a piano of minimum width. 65

The present invention contemplates the providing of a frame rectangular in form and having a movable member connected thereto, the several parts being so combined and arranged that the device is capable of being 70 practicably secured to, and of serving as a shield for pianos of different widths. This frame may be made of stout wood of any kind and stained to imitate ebony, oak, or mahogany or any other kind of wood or 75 finish, and comprises the end pieces A and A¹ whose ends are mortised, doweled, and glued to the ends of the side pieces B and B¹. At suitable locations near the ends of the piece B¹ are offsets B² which afford a 80 clearance for the free play or movement of the casters at the rear side of the piano body. Screws B³ in the side piece B¹ and near the offsets B² reinforce the piece B¹. Holes B⁴ and B⁵ are provided in the side pieces B and 85 B¹ respectively and their functions will presently be referred to. 90

An intermediate member connected loosely to and constituting a part of this improved shield consists of a bar C to whose end portions the heads C¹ of the peculiar construction shown in Fig. 1, are connected by screws C². The tongues C³ of these heads engage loosely the longitudinal slots A² of the end pieces A and A¹ of the frame. 95

A shield of the construction shown is applicable to use on the bases of pianos of the maximum or the minimum width. Applied to a piano of the maximum width the shield appears as shown in Fig. 3. The shield may be attached to the piano at the factory, or at the sales room. Before the piano is let down onto its casters, from the rocker, tip-over, or other style of truck upon which it may have been transported, the shield is attached 100 to its bottom. To so attach or fasten the shield in place, screws are passed through the holes B⁵ and through the holes B⁴, the former being screwed into the rear side of the base or bottom of the piano frame, and 105 110

the latter being screwed into the bottom of the toes K K of the piano legs. The intermediate member being then slipped forwardly until the bar C is in contact with the 5 side piece B there is ample room for the feet of the operator at the pedals L and L, and by virtue of the curvature C⁴ of the heads C¹ there is ample room for the free play or turning of the casters secured to the 10 toes K and K.

The mode of applying the device to pianos having less width—that is to say,—having toes extending not so far forwardly as do those of the wider class of piano, is identical 15 with that just described, except that in the last named width of piano, the connecting screws are passed through the holes C⁵ in the heads C¹ and screwed into the bottoms of the toes K¹, and the shield is held fast to the 20 bottom of the piano with the several parts in the relative positions as shown in Fig. 4.

The advantages afforded by this invention are obvious. With the edges of the side pieces and of the end pieces of the shield 25 projecting beyond the rear side, and beyond the ends of the body portion, and beyond the ends of the toes of the piano, possibility of injury by contact of articles of furniture or other objects, or of the broom or mop 30 splashing water or dirt against the polished surfaces of the piano or its toes or legs, is avoided. There being free play of the casters, the attachment of this shield at position as shown, does not interfere with or hinder 35 the usual shifting or moving about of the piano. It will be observed that there is ample room between the bar C and the face board M of the piano body for the feet of the person seated at the piano, so that use 40 of the pedals while the shield is in use as shown, is not interfered with. In manufacturing this improved shield in different

lengths no change in the construction shown, other than merely the lengthening of the side pieces and of the bar C, is necessary. 45

What I claim as my invention, and desire to secure by Letters Patent, is;—

1. A base shield for pianos, consisting of a rectangular frame, a longitudinal member having its ends connected to and movable slidingly in ways therefor in the end pieces of the frame, said frame and the said longitudinal member being capable of being attached to the bottom of the piano. 50

2. A base shield for pianos, consisting of a rectangular frame there being offsets in the inner edge of the rear side piece of the frame to afford clearance for the rear casters of the piano, a longitudinal member having its ends connected to and movable slidingly in ways therefor in the end pieces of the frame there being offsets in the said longitudinal member to afford clearance for the frontal casters of the piano, and the said frame and said longitudinal member being capable of 65 being attached to the bottom of the piano. 60

3. A base shield for pianos, consisting of a rectangular frame there being offsets in the inner edge of the rear side piece of the frame, and there being longitudinal grooves 70 in the inner faces of the end pieces of the frame, a longitudinal bar, a head piece secured to each end of the bar and having a tongue to engage said grooves in the end pieces of the frame, and there being an offset in the frontal side of each of the said head pieces. 75

In testimony whereof I affix my signature in presence of two witnesses.

CLARENCE COLEMAN.
